UNITED STATES PATENT OFFICE

2,074,791

RADIO AND LIKE SOCKET

Carl L. Knutson, Maywood, Ill., assignor to Cinch Manufacturing Corporation, Chicago, Ill., a corporation of Illinois

Application April 21, 1934, Serial No. 721,732

11 Claims. (Cl. 173—328)

My invention aims to provide improvements in sockets particularly, though not exclusively, useful in connection with the reception of the prongs of a radio tube.

5 In the drawing which illustrates a preferred embodiment of my invention:—

Figure 1 is a plan view of a preferred form of socket;

10 Fig. 2 is a bottom view of a preferred form 10 of socket;

Fig. 3 is a side elevation of the socket shown in Figs. 1 and 2;

Fig. 4 is an end elevation of the socket shown in Figs. 1 and 2;

15 Fig. 5 is a section taken on the line 5—5 of Figure 1;

Fig. 6 is a section taken on the line 6—6 of Figure 1;

Fig. 7 is a plan section taken on the line 7—7 of Fig. 3;

20 Fig. 8 is an enlarged section taken on the line 8—8 of Figure 1; and

Fig. 9 is a side elevation of the contact member per se.

25 The particular socket structure illustrated by the annexed drawing is formed with a top plate 1, a bottom plate 2, a plurality of contact members and means for securing the parts together. The top and bottom plates 1 and 2 are preferably formed from relatively thin, non-conducting material and are arranged in superposed spaced relation. A guide disk 3 is located in the center of the top plate 1 and is held in position by a fastener element, such as the bolt 4 (Fig. 5) or a rivet 5 (Figs. 3 and 7).

30 The top plate 1 has a plurality of apertures 6 and the bottom plate 2 has a plurality of apertures 7, as shown in Fig. 5. These apertures are in alignment with each other and located in a circle just outside the periphery of the guide plate 3 (Fig. 1) so that they may permit passage of the prongs of a radio tube or other like device with which the socket is adapted to cooperate.

35 Each contact member is formed from a single piece of relatively springy material and has a 45 pair of arms 8—8 paralleling each other but bent to provide a substantially circular opening between them, as shown in Fig. 7. The arms 8—8 are connected together at one end by a relatively wide loop portion 9, while the other ends are provided with projections 10—10 at one side and projections 11—11 at the opposite side the purposes of which will be more fully hereinafter described. Each contact is also provided with a soldering lug 12 extending from the loop portion

9 and adapted to have a suitable wire soldered or otherwise fastened thereto.

40 The contact members are assembled with the plates 1 and 2 in such a manner that each is associated with a hole 6 in the plate 1 and an aperture 7 in the plate 2. The assembly is such that all of the contact member, except the projections 10 and 11 and the soldering lug 12, is located in the space between the plates 1 and 2, as clearly illustrated by Figs. 4 and 6. The greater portion of each arm 8 is of less width than the space between the plates 1 and 2 (Fig. 6) so that it may be free to flex without interference from the plates. Thus only the loop portion 9 and the spacing portion 13 contact with the plates 1 and 2 to space the plates apart. The contact members are held in position by the projections 10—10 which extend through apertures 14 formed in the top plate 1, the projections 11—11 which extend through apertures 15 in the plate 2 and by the soldering lugs 12 which pass through notches 12^a in the plate 2, all as clearly illustrated at the right-hand side of Fig. 6. When the contact members are assembled with the plates 1 and 2 in the manner just described the relatively long flexible spring arms 8—8 are supported at both ends and intersect apertures 6 and 7, so that when prongs are forced between them they are much less likely to become set than would be the case if one or both ends were not supported. Furthermore, since the prong-engaging portions are spaced from the plates and do not pass through either of them they have greater flexibility and freedom of action than with any other type of arrangement of which I am aware.

45 While all of the contact members may be assembled between the plates 1 and 2 in such a manner that a line passing lengthwise between the arms 8—8 would be on a line radiating from the center of the rivet, as are some of the contacts (Fig. 7), I prefer to have some of them located on lines which are at an angle to radial lines. By arranging the contacts in this manner the apertures 14 and 15 are not in a circle thereby aiding in preventing relative rotation of the plates 1 and 2. Thus only a single rivet or bolt is necessary to hold the parts of the installation together and maintain proper alignment of the apertures 6 and 7 with the apertures 16 provided by the arms 8—8.

50 My improved socket is simple in construction, the parts are relatively easy to assemble and it is very durable, especially with respect to the construction and arrangement of the contact mem-

bers which receive the projections of a device with which the socket cooperates.

While I have illustrated and described a preferred embodiment of my invention, I do not wish 5 to be limited thereby, because the scope of my invention is best defined by the following claims.

I claim:

1. An electrical socket of the class described comprising, in combination, a pair of thin super- 10 posed spaced apart insulating plates, the top plate having apertures therethrough to permit passage of the prongs of a cooperating member, a plurality of contact members located between said plates, each of said contact members having 15 a pair of yieldable portions located beneath and intersecting an aperture in the top plate to receive a prong between them, and said yieldable portions being supported at both ends by said plates.

20 2. An electrical socket of the class described comprising, in combination, a pair of thin super- posed spaced apart insulating plates, each having a number of apertures in alignment with the other to permit passage of the prongs of a coop- 25 erating member, a plurality of contact members located between said plates, each of said contact members having a pair of yieldable portions located between and wholly protected by said plates and intersecting an aperture in the top 30 plate to receive a prong between them and each of said yieldable portions having a projection at the free ends extending into an aperture in one of said plates to prevent movement of said contact members in relation to the plate with which 35 they are interlocked, and a means associated with said socket for preventing the rotation of one of said plates relative to the other of said plates and the contact members attached thereto.

3. An electrical socket of the class described 40 comprising, in combination, a pair of superposed spaced apart insulating plates, the top plate having apertures therethrough to permit passage of the prongs of a cooperating member, a plurality of contact members located between said plates, 45 each of said contact members having a pair of free ended yieldable portions located beneath and intersecting an aperture in the top plate to receive a prong between them and each of said yieldable portions having a pair of oppositely extending 50 projections at the free ends extending into cooperating apertures in the plate members.

4. An electrical socket of the class described comprising, in combination, a pair of superposed spaced apart insulating plates, the top plate hav- 55 ing apertures therethrough to permit passage of the prongs of a cooperating member, a plurality of contact members located between said plates, each of said contact members having a pair of yieldable portions connected together at one end 60 and being located beneath and intersecting an aperture in said top plate, a soldering lug ex- tending from said connected end and the opposite free ends having plate-engaging means ex- tending into a hole in one of said plates, said 65 means comprising integral projections extending at an angle from said free ends for preventing movement of said yieldable portions relative to the apertures which they intersect.

5. An electrical socket of the class described 70 comprising, in combination, a pair of superposed spaced apart insulating plates, the top plate having apertures therethrough to permit passage of the prongs of a cooperating member, a plurality of contact members located between said plates, 75 each of said contact members having a pair of

yieldable portions connected together at one end and being located beneath and intersecting an aperture in said top plate said contact members being held substantially flush between said plates by engagement therewith at both ends thereof, 5 and said portions being of less width for a portion of their lengths than the width of the space between the plates to permit freedom of yielding action thereof.

6. An electrical socket of the class described 10 comprising, in combination, a pair of superposed spaced apart insulating plates, the top plate having apertures therethrough to permit passage of the prongs of a cooperating member, a plurality 15 of contact members located between said plates, each of said contact members having a pair of yieldable portions connected together at one end and being located beneath and intersecting an aperture in said top plate, a soldering lug extending from said connected end and engaging one 20 of the plates and each of the free ends having plate-engaging projections extending into holes in said plates and a single fastening unit passing through the plate members, substantially centrally with respect to the apertures in the top 25 plate, to secure the parts of the socket together.

7. An electrical socket of the class described comprising, in combination, a pair of superposed spaced apart insulating plates each having a 30 number of apertures in alignment with the other to permit the passage of the prongs of a cooperating member and contact members having yieldable portions located entirely between said plates and intersecting said apertures to make electrical connection with the said prongs, said contact 35 members also having plate-spacing portions interlocking both of the plates whereby a plurality of contact members serve to space the plates one from another and hold the apertures in both blades in proper alignment to receive the prongs 40 of the cooperating member.

8. An electrical socket of the class described comprising, in combination, a pair of superposed spaced apart insulating plates each having a 45 number of apertures in alignment with the other to permit the passage of the prongs of a cooperating member and contact members having yieldable portions located entirely between said plates and intersecting said apertures to make electrical connection with the said prongs and at least some of said contact members extending 50 between said plates in lines angled relative to radial lines from the center of said socket, each of said contact members having interlocking engagement with both of said spaced insulating plates whereby tendency of relative rotation between said plates is restrained by said contact 55 members.

9. An electrical socket of the class described comprising, in combination, a pair of superposed spaced apart insulating plates each having a 60 number of apertures in alignment with the other to permit the passage of the prongs of a cooperating member and contact members having yieldable portions located entirely between said plates and intersecting said apertures to make electrical connection with the said prongs and each of said contact members having a pair of yieldable arms connected together at one end by a loop portion providing a spacer for the two 65 plates and having plate-engaging projections at their free ends extending from plate-spacing means also provided at the free ends, means at the loop and free ends of the contact members acting to space the insulating plates one from 70 75

another, said plate-engaging projections extending into a hole in one of said plates and a means associated with said socket whereby the apertures of said plates are held in proper alignment 5 to receive the prongs of the cooperating member.

10. An electrical socket of the class described comprising, in combination, a pair of superposed spaced apart insulating plates each having a 10 number of apertures in alignment with the other and spaced about the center of each plate to permit the passage of the prongs of a cooperating member and contact members having free ended yieldable portions located entirely between 15 said plates and intersecting said apertures to make electrical connection with the said prongs and each of said contact members having a pair of yieldable arms connected together at one end by a loop portion providing a spacer for the two 20 plates and having oppositely-directed plate-engaging projections on each of their free ends extending from plate-spacing means also provided at the free ends for interlocking with the plates, a soldering lug extending from the looped 25 end and a single attaching member passing

through both plates at their centers and providing the only means for holding the parts of the socket in assembled relation.

11. An electrical socket of the class described comprising, in combination, a pair of superposed spaced apart insulating plates each having a 5 number of apertures in alignment with the other to permit the passage of the prongs of a cooperating member and contact members located between said plates and having yieldable portions intersecting said apertures to make electrical connections with said prongs, each of said contact members having spacers at both ends thereof acting as a means to maintain the plates in spaced parallel relationship, one of said ends 10 having a projection integral with said corresponding spacer interlocking with one of said plates for preventing movement of said contact members relative to said last mentioned plate, and means associated with said socket for preventing the rotation of the other of said plates 15 relative to the plate to which said contact members are attached.

another, said plate-engaging projections extending into a hole in one of said plates and a means associated with said socket whereby the apertures of said plates are held in proper alignment 5 to receive the prongs of the cooperating member.

10. An electrical socket of the class described comprising, in combination, a pair of superposed spaced apart insulating plates each having a 10 number of apertures in alignment with the other and spaced about the center of each plate to permit the passage of the prongs of a cooperating member and contact members having free ended yieldable portions located entirely between 15 said plates and intersecting said apertures to make electrical connection with the said prongs and each of said contact members having a pair of yieldable arms connected together at one end by a loop portion providing a spacer for the two 20 plates and having oppositely-directed plate-engaging projections on each of their free ends extending from plate-spacing means also provided at the free ends for interlocking with the plates, a soldering lug extending from the looped 25 end and a single attaching member passing

through both plates at their centers and providing the only means for holding the parts of the socket in assembled relation.

11. An electrical socket of the class described comprising, in combination, a pair of superposed spaced apart insulating plates each having a 5 number of apertures in alignment with the other to permit the passage of the prongs of a cooperating member and contact members located between said plates and having yieldable portions intersecting said apertures to make electrical connections with said prongs, each of said contact members having spacers at both ends thereof acting as a means to maintain the plates in spaced parallel relationship, one of said ends 10 having a projection integral with said corresponding spacer interlocking with one of said plates for preventing movement of said contact members relative to said last mentioned plate, and means associated with said socket for preventing the rotation of the other of said plates 15 relative to the plate to which said contact members are attached.
